W.W. Merriam,

Boot and Shoe Patterns,

No 18,594,

Patented Nov. 10, 1857.

Sec. II.

Sec. I.

UNITED STATES PATENT OFFICE.

W. W. MERRIAM, OF OSWEGO, NEW YORK.

PATTERNS FOR CUTTING OUT THE UPPERS OF BOOTS AND SHOES.

Specification of Letters Patent No. 18,594, dated November 10, 1857.

To all whom it may concern:

Be it known that I, W. W. MERRIAM, of Oswego, in the county of Oswego and State of New York, have invented certain new and useful Improvements in Adjustable Patterns for Measuring and Shaping the Uppers of Shoes and Boots; and I do hereby declare that the following is a full, clear, and exact description of the same, reference being had to the accompanying drawings, in which—

The figures in Section I, represent the parts composing the pattern for the uppers of a shoe or gaiter. The figures of Section II, represent the parts composing the pattern for a boot leg. The figures in Section III, represent the parts composing the pattern for the uppers of a boot. The figures in Section IV, represent the parts composing the pattern for the uppers of a boot previous to being crimped.

The nature of my invention consists in making my patterns adjustable independently in different directions, thus affording the means of adapting said patterns to the various sizes, as well as to various proportions of the same side of the thing or pattern to be cut.

To enable others skilled in the art to make and use my invention I will proceed to describe the construction and operation of each of the above named patterns *seriatim*.

In Section I, of the drawings Figure 1, represents the pattern for the uppers of a gaiter. Fig. 2, represents the reversed side of said pattern; Fig. 3 represents the sliding plates of said pattern in their most contracted position; Fig. 4 represents said sliding plates when extended; Figs. 5 and 6 represent detached views of the sliding plates.

The plates A, and B, of Figs. 1 and 2, represent the outside plates of the gaiter pattern which are permanently secured to each other by means of the rivets *a*, said plates being kept apart by intervening washers sufficiently to allow a free play of the parts C, D, E, F, G, H, between them. The parts C and D, are connected to each other by rivets *b*, which are secured to part C, and pass through the slots *c* of plate D, which can thus be run in and out on said rivets. The plate C, is connected with plate B, by means of rivet *d*, which passes through slot *e*, of plate B, and with plate A by means of

screw *f*, which passes through slot *g*, of plate A. The plates E and F, are connected to each other by rivets *h* and *i*, which pass through slots *k* of plate F, the rivet *i*, passing also through slot *l*, of the plate B. The operation of these plates is as follows: By moving screw *f* within slot *g*, the plate C, will be pushed outward as represented in Fig. 4, it being guided by pins *f*, and *d*, which run in their respective slots *g*, *e*, the plate C, carrying with it the plate D. By moving the pin *m*, in its slot *o*, the plates E, and F, are moved simultaneously outward as represented in Fig. 4, they being guided by pins *m*, *a*, and *i*, the pins *m* and *i* running in slots *o*, and *l*, and by lastly moving the pin *n* within its slot *p*, the plates F, and D, are pushed in the longitudinal direction of the foot they being operated upon by levers G, H, and guided in their motion by pins *b*, *h*, and *i*, running in their respective slots. Thus it will be seen that the length, width, and height of this pattern can be adjusted separately and independently of each other, each of these movements being effected by operating the respective pin *f*, *m*, or *n*, in its slot, and the parts can then be secured to any desired position by tightening the screw nuts of said pins or screws, the graduated scales *x*, *y*, and *z*, serve to facilitate the operation of adjusting the several parts to any desired position from that shown in Fig. 3, in which the parts are represented in their most contracted positions. The mode herein described of operating the various plates independently of each other is made use of in the patterns hereafter to be described for producing a similar effect.

In Section II, Fig. 1, represents the pattern of a boot leg. Fig. 2, represents the same pattern exposing the adjustable sliding plates, in their most contracted positions; Fig. 3, represents the pattern showing the sliding plates in their most expanded position. This pattern consists of two equally shaped plates, one of which is represented at F Fig. 1, which are riveted together by means of rivets *a*, and which are sufficiently distended by intervening washers to allow free play between them of the sliding plates A, B, C, D, E. The pin *b*, of the slide G, is sunk into the rear side of plate E, Fig. 3, and by moving the slide G from the right to the left pin *b*, is traversed in slot C, carrying plate E, with it

while the pins *d*, of plate *E*, operate upon the oblique slots *e*, of plates *B*, pushing said plates outward, thereby enlarging the width of the pattern. To preserve the shape of the pattern the plates *B*, have to be moved slightly to the left during their outward motion, and this is accomplished by pins *f*, which pass within the oblique slots *g*; the plates *B*, by their outward motion carry with them the plates *D*, and *C*, without imparting to them a longitudinal motion as said plates are guided by pins *h* and *i* playing with their respective slots *k* and *l*. The pin *m* which slides through slot *n*, is secured to plate *A*, and by operating said pin, the pattern can be elongated, the plate *A*, carrying with it the plates *D*. Thus the width of the pattern can be adjusted by operating slide *G*, and the length of the same can be adjusted by operating pin or screw *m*, the pattern can be secured to any desired position by screw nuts as described above.

The figures in Section III, represent the pattern for the uppers of a boot when already crimped. Fig. 1, represents the pattern in its most contracted position; Fig. 2, represents the sliding plates of the foot part, and Fig. 3, those of the leg part, both in their most contracted position; Figs. 4 and 5, represent the sliding plates of the foot and leg part both in their most extended positions. This pattern also consists of two outside plates *A* and *B*; of the latter only that part is represented in the drawings which shows the working parts; the plates *A* and *B*, are riveted together by rivets *a*, the plates *C*, *D*, *E*, *F*, *G*, having free play between them as in the preceding patterns. The pin *b*, of the slide *I*, is secured to plate *H*, said pin passing through slot *c*, in plate *A*, and through slot *d*, in plate *G*, the other pin *f* of plate *H*, passes through slot *e*, of plate *G*, by moving slide *I*, downward, the pins *b* and *f*, operating within the oblique parallel grooves *d*, *e*, force the plate *G*, outward to the position represented in Fig. 5, thereby widening the leg part of the pattern. The plates *G*, as it is moved outward, also moves slightly downward by means of the pin *g* working in the oblique grooves *h*, for the purpose of retaining the relative position between the curved end *L*, and the foot part of the pattern, while the plate *F* is moved outward simultaneously with the plate *G*, by means of the guide pins *i*, running in the grooves *k*. The foot portion of this pattern is operated independently of the leg portion by means of the slide *K*, and the pin or screw *m*. By moving screw *m* downward in slot *O*, the plates *C* and *D*, are moved downward, they being guided by screw *m*, and pins *p* and *q*, moving within their respective slots *r*, and *s*, as represented in Fig. 4, the foot can be elongated by sliding pin *n*, within its groove

u, when the plates *D* and *E*, will be pushed in the longitudinal direction of the foot they being guided by pins *a*, *q*, and *v*, and their respective slots *x*, *y*, *z*, the connection between the plates *D*, and *E*, being established by pin *t* sliding within groove *P*. Thus by the arrangement of these slides the width of the leg part can be adjusted independently of any of the dimensions of the foot and vice versa.

In section IV, the pattern for the upper of a boot is represented as being spread out, or before being crimped. Fig. 1, represents the pattern in its contracted position, Fig. 2 represents the sliding parts in their contracted positions, and Fig. 3 the same parts in their most extended positions, the two outside plates one of which is represented in Fig. 1, are riveted together by means of rivets *a*. The pin *b*, of the slide *H*, is secured to plate *A*, and as said pin is moved in slot *c*, the plate *A*, is moved in the longitudinal direction of the pattern it being guided by pins *d*, and *e*, sliding within the grooves *f* and *g*. This movement of the plate *A* causes the plates *B*, *D*, *E*, *F*, to move in a transverse direction to the pattern to the position represented in Fig. 3 by the following arrangement of parts: The pins *h'*, *h''*, *l''*, pass respectively through the oblique slots *i* and *k* of the plates *D*, and through the slots *m* and *n* of the plates *E*, thereby driving said plates outward in opposite directions, they being guided in their movement by pins *a*, *o*, and *r*, passing through slots *q*, *p*, and *s*. The plates *F*, are connected with plates *E*, by pins *w*, moving in slots *x*, and pins *y*, moving in slots *z*, and the plates *B*, are connected with plates *D*, by pins *a'* passing through slots *b'*, and thus the plates *B*, *D*, *E*, *F*, move simultaneously. It will be observed that the slots *k* and *m* in the plates *D*, and *E*, in which the pivots *h''* play are not parallel; this is for the purpose of moving the plates *D*, farther out than the plates *E*, and by these means to preserve the shape of the pattern at the curve *L*.

The pivot *d'* of the slide *N*, Fig. 1, is secured to plate *C*, and by operating said pivot within groove *(e')* plate *C*, is pushed outward, and the toe end of the pattern is extended, the plates *B*, being operated simultaneously with plate *C* by their connecting pin *g'*, sliding within the grooves *m'*, while the plates *B*, are guided by pins *a'*, so as to preserve the shape of the pattern. The pin or screw *O'*, Fig. 1, is secured to plate *G*, and by operating said pin within its groove *p'*, the part *G* together with plates *F* is extended to the position represented in Fig. 3, they being guided by pins *w*, running in slots *x*.

Having thus fully described the nature of my invention, I would state that I do not lay any claim to an extension pattern, which

can be operated in such a manner as to produce the various sizes of patterns, but

What I do claim as new and desire to secure by Letters Patent is—

5 The method herein described of operating the sliding parts of an extension pattern so as to adjust the same not only to different sizes, but also to change the proportions of

the several sizes at pleasure without regard to the whole, substantially as herein set forth.

W. W. MERRIAM.
